UNITED STATES PATENT OFFICE.

AUSTIN J. RUPPERT, OF FORRESTON, ILLINOIS.

WEIGHING AND MEASURING MACHINE.

Application filed March 26, 1927. Serial No. 173,643.

My invention relates to automatically operated weighing and measuring machines and one of the objects of the invention is to provide a device which is operated under its own power, after the material starts running into or is delivered into the machine. The machine can be used in connection with fluent materials such as sand, gravel, talc silicate, crushed rock, coal, mica and the like.

Referring to the drawings for a more complete disclosures of the member

Fig. 1 is a side elevation;

Fig. 2 is a vertical section of Fig. 1;

Fig. 3 is a section on the line 3—3 of Fig. 2;

Fig. 4 is an enlarged section on the line 4—4 of Fig. 2;

Fig. 5 is a detail section on the line 5—5 of Fig. 2.

The machine comprises a stationary portion 1 and a rotor 2 mounted to rotate relative to the stationary portion.

The stationary portion has side plates 3 made out of tank or boiler steel and other stock shapes. Connecting the side plates at their upper parts is a bottom plate 4 and a bottom plate 5 which together form a receiving hopper for the material as it is dumped in. These plates are connected to the sides 3 by means of angle irons 6. The inner or adjacent ends of the plates 4 and 5 are separated sufficiently to permit the material to flow therethrough into the rotor 2. In order to break the fall of the material as it is dumped into the hopper, I provide a transverse baffle plate 7, bolted to the side plates 3, by angle irons 8. Bolted to the lower side of the side plates is a discharge plate 9.

It will be noted that the side plates which act as braces or supports for the rotor, at the same time also form a part of the receiving hopper.

Attached to the bottom of the steel plates and bolted firmly thereto are angles 30 which form a support for the machine.

Secured to the side plates 3 is a sacker 10, which is used when it is desired that the discharged material shall be dumped into sacks, there being a space 11 between the discharge plate 9 and the sacker 10, through which the material flows.

The side plates 3 will be further held together by cross bars 12 and cross plates 13.

The rotor comprises two circular side

plates 14 mounted on a shaft 15. Cross-bars 16 and 17 rigidly connect the said plates. The rotor is divided into a number of compartments five being shown. These compartments are formed by separator sheets 31 extending from one side plate to the other and being secured thereto, the said sheets also being secured to the cross bars 16 and 17 and lying close to the shaft 15 and tangential thereto.

The separator sheets are so laid on the shaft 15 that any water in the material will run out of the V at the bottom of the pocket and onto the opposed underlying sheet.

Mounted in the side frames 3 is a stub axle 3' and rotating about this axle is a toothed quadrant 18. Rotatably mounted in the body of the quadrant is the end 19 of the shaft 15. Both of these rotatable connections may be mounted in ball bearings 20 and 21. In the side plates 3, a suitably shaped slot 22 may be cut and as the quadrant rotates about the stub axle the shaft 15 travels in the slot. Also mounted to rotate on ball bearings 24 in the side plate 3 is the gear 23 which meshes with the toothed quadrant 18. Secured to the said gear is the weight arm 25 carrying the slidably adjustable weight 26.

Secured to the side plates 3 is a slotted and slidably adjustable hard steel bar 27 against which the tool steel lug 28 contacts to act as a stop. The lugs 28 will be bolted directly to the outside of the rotor and the bars 27 will be bolted to the inside of the side plates 3 and will be ground so as to be true with the dead center of the shaft 15 to prevent unevenness of the rotor and take the shock or jar off of the rotor when revolving or turning to a new position for filling.

Connected to the side plates 3 is a hard steel bar 29 against which the cross bar 16 just contacts when the rotor is at rest. The particular arrangement of stops and cross bars is simply a means of lining up the parts used in the machine as well as to take the hardest part of the work off of the cross bars 16 and 29, the idea being to have the stops contact just before the cross bars actually touch each other.

When the rotor gradually sinks down under the combined weight of its own material plus the weight of the measured material flowing into the pocket, the top edge of the steel bar 16 will be on a level with the bottom of the steel trip bar 29 and thus per-

mits the rotor to slip past this point and turn to the right. As the motor turns to the right, the material in the pocket is discharged onto the plate 9. As the material discharges, the motor under the influence of the weight 26, rises to its proper position and the bar 16 on the next succeeding pocket will then contact with the bar 29. When the rotor is at its highest point and being loaded, the bar 16 is sufficiently above the bottom of the bar 29 to entirely shut off all material from flowing into the next pocket, until the loading pocket is actually filled and ready to be discharged.

15 As the rotor gradually sinks downwards, it causes the axle 15 to pull the geared quadrant downwards in an arc of a circle about the axle 17, the axle 15 being free to run up and down in the slot 22. While the 20 teeth of the quadrant are turning about the axle 17, the geared hub 23 also turns lifting the weight 26. The weight 26 can be adjusted on the arm 25 to vary with the weight of the material in the pockets, as 25 desired. The arm 25 can be graduated to accurately weigh wherever the weight is set.

My machine as well as each and all of its parts are simple in design and readily accessible in assembling, repairing or replacing 20 parts.

My machine will weigh or measure its rated load, using only one weight on each side and neither one need ordinarily be heavier than 30 lbs.

35 In my machine, the steel bar 16 stabilizes the weight of the rotor from two sides at once, so that both sides of the rotor are perfectly balanced, while the bar 16 trips under the bar 29, evenly from one end to the other, so that there is no twisting or weaving in 40 weighing and tripping.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to 45 indicate the scope of my invention.

Having described my invention what I claim as new and desire to secure Letters Patent for is:

1. In a device of the character described,

a horizontal rotatable receptacle, side plates 55 forming a support for the said receptacle, bottom plates connecting the side plates above the receptacle to form a hopper for feeding material into the receptacle.

2. In a device of the character described, 60 the combination of a horizontal rotatable receptacle, an axle upon which it is mounted, separator sheets dividing the receptacle into compartments, one end of the said sheets lying on the axle tangentially and permitting seepage of water therebetween.

3. In a device of the character described, a horizontal rotatable receptacle, side plates forming a support for the said receptacle, bottom plates connecting the side plates 70 above the receptacle to form a hopper for feeding material into the receptacle, and a baffle plate between the side plates to break the fall of the material as it is fed into the hopper.

4. In a device of the character described, the combination of a rotary receptacle, side plates forming a support for the said receptacle, a shaft for the receptacle, the ends of the shaft passing through slots in the side 80 plates, a toothed sector pivotally mounted on the side plates, the ends of the shaft being rotatably mounted in the sector and a counter weight cooperating with the sector.

5. In a device of the character described, 85 the combination of a rotary receptacle having a plurality of compartments, side plates forming a support for the said receptacle, a hopper above the compartments, the separator sheet between the compartment being 90 filled and the succeeding compartment, being closely adjacent the discharge opening in the hopper during the filling operation, a cross bar connecting the side plates, another cross bar connecting the sides of the rotary receptacle, the two said cross bars acting as a stop for limiting the rotary movement of the receptacle and also to prevent material flowing into the succeeding compartment during the filling operation, and means 100 for disengaging the said bars by the downward movement of the receptacle to permit the said receptacle to rotate, the stream of material from the hopper being uninterrupted during the rotary movement of the 105 receptacle.

In testimony whereof I affix my signature.

AUSTIN J. RUPPERT.
